UNITED STATES PATENT OFFICE

2,073,410

ABSORBENT PACKAGE OR PAD

Errol B. Thomas, Newton, Mass., assignor to
 International Cellucotton Products Company,
 Chicago, Ill., a corporation of Delaware

Refiled for abandoned application Serial No.
 77,786, December 26, 1925. This application
 October 9, 1934, Serial No. 747,594

3 Claims. (Cl. 128—290)

My invention relates to packages or pads of absorbent material, of general use for absorptive purposes but particularly adapted for use in sanitary napkins. More particularly my invention 5 aims to provide an improved and less expensive material and article of the class described, including means for controlling or directing its absorptive action. This application is a re-filing, with identical disclosure of the means of my invention, of my previous application S. N. 77,786, filed December 26, 1925.

It has heretofore been proposed to employ in forming absorptive pads a relatively large plurality of layers or webs of extremely tenuous and 15 film-like wood cellulose material, generally some thirty-five to forty of such webs being superposed. Said webs are each separately formed, and because of their extreme thinness require slow and careful handling during the process of 20 manufacture and in forming the pads. They cannot be run rapidly through the rollers, drums and the like necessarily employed in the production of the same. The expense of manufacture is further increased by the fact that special machinery 25 or special and costly adaptation of the usual pulp handling machinery is required.

For the purpose of decreasing manufacturing costs, and at the same time providing an improved product, in accordance with my present 30 invention, I employ a less number of layers or webs of wood cellulose which, while thin as compared with the thickness of the absorbent pad as a whole, have sufficient substance and are of such consistency as to be susceptible of rapid handling 35 and by machinery of the standard form generally used in mills manufacturing from wood pulp.

In the drawing illustrating embodiments of certain forms of my invention:—

Fig. 1 is a vertical section showing a layer or 40 web of the cellulose material in the form in which it comes from the web-forming machinery;

Fig. 2 is an expanded view, in perspective, of a plural-layer absorbent pad embodying one form 45 of my invention;

Fig. 3 is a similar view, showing the pad assembled, portions of the upper layers being broken away;

Fig. 4 is a corresponding view showing a pad 50 with modified form of absorption controlling means;

Fig. 5 is a perspective view of layers of absorptive material illustrating another arrangement of absorption controlling or directing means in 55 accordance with my invention; and

Fig. 6 is a view similar to Fig. 5 showing a further modification of absorption controlling means embodying my invention.

Referring now more particularly to the drawing, I have shown at the left in Fig. 1 a web or 5 layer 1 of the wood cellulose material as it comes from the drums and rollers of the web-forming machinery. At that time the web has substantially the consistency, form, and surface characteristics of ordinary blotting paper, and is preferably of about the thickness of that product. It may be formed by means of the usual machinery employed in producing blotting paper and the like, without necessitating any rearrangement or costly change in such machinery, thus making it 15 possible to use the same machines and to shift readily from the manufacture of the present product to another without additional expense. The cellulosic material of which said webs are formed is preferably wood cellulose of the so-called "alpha fibre" type, consisting of a soft wood pulp, such as pine, from which practically all traces of pitch and tar have been removed.

So far as I am aware webs of wood cellulose of 20 said form and character have not heretofore been 25 employed or suggested for use in connection with absorptive packages for sanitary napkins or the like, and in the form so far described are wholly unsuited for such use because of their stiffness, 30 harshness, surface matting of the fibres, etc.

As illustrated in Fig. 1, the webs in their stiff, 35 fibre-matted condition in which they come from the web-forming machinery, as indicated at 1, are subjected to a softening, fluffing, napping, crumpling, or other like action spreading and 40 separating the fibers, on both faces of the web. The means herein shown by way of example for effecting said operation comprises the upper and lower rolls 2, 3 rotatably supported in position to permit passage of the web between them, 45 suitable guides 4, 5 for the web being provided. Said rolls have web-engaging surfaces formed of coarse sand-paper, radial wires, bristles, teeth, or the like, and preferably are driven at slightly different speeds so as to subject the webs to a 50 differential or brushing action in addition to the picking, napping, fluffing or like softening and surface-matting destroying action.

By said means the web 6 issuing from the delivery guides 5 is rendered extremely soft and 55 pliable, having both faces fluffed and relieved of surface matting of the fibres. Both in appearance and to the touch the webs thus treated so closely resemble natural short-staple absorbent cotton as to be scarcely distinguishable from it.

I thus provide a material in web or sheet form which is admirably suited for use in absorbent packages, being clean, highly absorbent, and inexpensive in manufacture. An efficient absorptive package may be formed from about seven layers or webs superposed and cut to the desired size, as illustrated; obviously a greater or a less number of such layers may be employed if desired.

10 In a package or pad formed of the material as described the natural absorptive action is substantially the same in all directions in the plane of the web, and is somewhat greater in that plane than in the direction through the pad.

15 For some purposes this is wholly desirable, but in a pad for use in a sanitary napkin an objection arises which, unless remedied, would tend to outweigh the numerous advantages already mentioned.

20 In a sanitary napkin the absorbent pad is somewhat elongated, having a length preferably from two to three times the width of the pad. Equal rate of absorption in all directions in the plane of the webs is advantageous, even in this 25 case up to a certain point, since a greater lateral extent of the pad is brought into use, as compared for example with elongated pads formed of a greater number of extremely thin webs, previously referred to, having a longitudinal grain 30 resulting from necessary craping or the like and in which the absorption is much greater longitudinally of the pad and too limited in the lateral direction.

But this advantage extends only to a certain 35 point, namely, where the maximum desired lateral spread is reached. Beyond that point the ability of the pad to absorb equally rapidly in all directions in the plane of the webs becomes a disadvantage in an elongated pad, since the fluid 40 may spread by absorption to the outer side edges of the pad, with undesirable results, before the desired longitudinal extent of the pad has come into action.

My invention therefore includes a method and 45 means for controlling or directing the absorptive action, and whereby the absorption may be made to take place laterally of the pad to the desired extent but not beyond, and also at a greater rate downwardly in the direction through 50 the pad and over the entire available area of the pad rather than locally only.

For this purpose, as clearly seen in Figs. 2 and 3, one or more of the webs, starting at the upper 55 face of the pad, are provided with one or more cuts, slits, or like formations 7, desirably substantially parallel when a plurality is employed, and extending in a direction approximately perpendicular to that direction in the plane of the web in which it is desired to decrease the absorptive efficiency. Said cuts or slits preferably are each substantially continuous, as in Figs. 2 and 3, and in Fig. 6, in which latter each such formation comprises a series of shorter cuts or slits 7'. Each such formation has an overall 60 length approximately that of the area over which absorption is desired, but not exceeding such length. Desirably they terminate sufficiently short of the end edges to preserve the structural strength of the pad.

70 By means of said slit-like formations the lateral absorption in the slitted web is impeded or wholly checked. The absorptive action is directed and controlled since the fluid will not readily cross from one slit edge to the opposite 75 one, even though slitted edges are in contact or

substantially so, but will be forced to spread in the direction of the slits and downwardly through the web and into the next lower web or webs. Preferably the number and arrangement of the slits are such that the resultant absorption will be distributed evenly over the entire available area, that is, the area which it is permissible or desirable to employ. The proper longitudinal distribution will have taken place in substantially the same time as the less extensive and retarded lateral distribution, while the down-absorption simultaneously is materially increased and more evenly distributed.

10 In Figs. 2 and 3 I have illustrated four slits in the upper or first web, which, being the first to receive the fluids, requires the greatest direction or control of its absorptive action. The number of slits may be increased or decreased according to different conditions. Also in the succeeding layers or webs the number of slits may be progressively decreased or otherwise varied toward the bottom of the pad. By way of example, in said Figs. 2 and 3, I have shown three slits in the second web, two in the third, three in the fourth, two in the fifth, and one in the sixth or next to the bottom web, and none in the last or bottom web. It will be understood that the number of layers or webs may also be varied.

15 If a less increase of the downward absorptive action is desired, the slits in succeeding webs may be differently spaced apart, staggered or otherwise arranged so as not to come one directly beneath or above another, as in said Figs. 2 and 3; or if a greater down absorption and somewhat less limited lateral absorption is desirable an arrangement similar to that of Fig. 4 may be employed, wherein I have shown four slits in each of the first two webs, and in coinciding positions, two slits in each of the two succeeding webs, also in coinciding position but differing from the position of the slits in the first webs, the remaining webs being unslitted. The arrangement and number of slits, and the number of webs slitted, may thus be widely varied in accordance with the circumstances and with the results desired.

20 In some instances it has been found useful to arrange the slits somewhat on the bias, as shown in Fig. 5, the slits 7 being inclined at any desired angle to the longitudinal axis of the pad, and in either direction, preferably not exceeding 45°, so that their general direction remains lengthwise the pad.

25 As above pointed out the described method and structure result not only in properly limiting the lateral absorption but also in increasing the down absorption, which latter is made to occur not locally merely but over the entire available area of the pad. Any possible leakage at the bottom of the pad is desirably prevented by suitable moisture-proofing means 8, preferably such as disclosed in my Patent No. 1,564,498, dated December 8, 1925, and the Reissue No. 16,603 thereof.

30 My invention is not limited to the particular embodiments thereof shown and described by way of illustration, its scope being set forth in the appended claims.

I claim:

1. An absorbent pad particularly adapted for 70 use in a sanitary napkin, comprising a plurality of superposed webs of cellulose material relatively thick as compared with a tenuous film and wherein the absorptive rate is normally substantially equal in all directions in the plane of a web, 75

- certain of said webs having one or more substantially continuous slit-like formations extending in a general direction approximately at right angles to the direction in which it is desired to limit the rate of absorption, and of a length less than the dimension of the pad in the direction of their extent, each web so formed having a peripherally continuous and non-slitted marginal portion integrally enclosing the same.
- 5 2. An absorbent pad particularly adapted for use in a sanitary napkin, comprising a generally elongated, flattened pad of absorbent cellulosic material, the pad being formed of a plurality of relatively superposed sheets of said material and being provided with a slit-like formation extending generally longitudinally of the pad, said slit-like formation serving to cause the area of absorp-
- 10
- 15

tion in the pad to be elongated longitudinally of the pad from a localized area of fluid application disposed more or less centrally of the pad.

3. An absorbent pad particularly adapted for use in a sanitary napkin, comprising a generally elongated, flattened pad of absorbent cellulosic material, the pad being formed of a plurality of relatively superposed sheets of said material, said pad having a web of sheet material disposed intermediate its thickness and provided with a slit-like formation extending generally longitudinally of the pad, said slit-like formation serving to cause the area of absorption in the pad to be elongated longitudinally of the pad from a localized area of fluid application disposed more or less centrally of the pad.
